(57) **CLAIM**

The ornamental design for a cigar case with a humidity pack slot, as shown and described.

DESCRIPTION

FIG. 1 is a bottom perspective view of a cigar case with a humidity pack slot, showing a first embodiment of my new design;

FIG. 2 is a partially exploded perspective view of FIG. 1 shown in an environment of use;

FIG. 3 is an exploded top perspective view of FIG. 1;

FIG. 4 is an exploded top plan view of FIG. 1 shown with each component side by side and environment removed for clarity of disclosure;

FIG. 5 is a bottom plan view thereof;

FIG. 6 is a left-side elevational view thereof;

FIG. 7 is a front elevational view thereof;

FIG. 8 is a rear elevational view thereof;

FIG. 9 is a bottom perspective view of a second embodiment thereof;

FIG. 10 is a partially exploded perspective view of FIG. 9 shown in an environment of use;

FIG. 11 is an exploded top perspective view of FIG. 9;

FIG. 12 is an exploded top plan view of FIG. 9 shown with each component side by side and environment removed for clarity of disclosure;

FIG. 13 is a bottom plan view thereof;

FIG. 14 is a left-side elevational view thereof;

FIG. 15 is a front elevational view thereof; and,

FIG. 16 is a rear elevational view thereof.

The broke lines illustrated in FIGS. 1-5, 7, 9-13, and 15 depict portions of the cigar case with a humidity pack slot that form no part of the claimed design. The additional broken lines illustrated in FIGS. 2, 3, 10, and 11 depict a cigar and humidity pack as environmental subject matter only that form no part of the claimed design.
